(57) **CLAIM**

The ornamental design for a massage device, as shown and described.

DESCRIPTION

FIG. 1 is a front perspective view of a massage device according to my new design;

FIG. 2 is a front view of the massage device of FIG. 1;

FIG. 3 is a rear view of the massage device of FIG. 1;

FIG. 4 is a side view of the massage device of FIG. 1, to which an opposite side view is a mirror image thereof;

FIG. 5 is a top view of the massage device of FIG. 1; and,

FIG. 6 is a bottom view of the massage device of FIG. 1.

Elements shown in broken lines show environmental structures of the massage device and form no part of our design.

1 Claim, 6 Drawing Sheets
